175,969

PIN OR SIMILAR ARTICLE

Lucy M. Mahlberg, Littleton, Colo., assignor of one-third to Herman Wehling, Denver, Colo., and one-third to Lawrence Mahlberg, Littleton, Colo.

Application March 5, 1954, Serial No. 29,355

Term of patent 14 years

(Cl. D45—19)

FIG. 1.

FIG. 2.

Fig. 1 is a front elevation view of a pin embodying my new design;

Fig. 2 is a side elevation of the pin of Fig. 1.

The essential elements of my design are shown in full lines in the drawing.

I claim:

The ornamental design for a pin or similar article, as shown and described.
